Application December 26, 1933, Serial No. 703,952

11 Claims. (Cl. 263—21)

This invention relates to apparatus for forming dispersions of materials such as relatively finely divided solids. In many of the arts it is desirable to produce dispersions of materials for the purpose of promoting reactions between such materials and other substances, for example, to facilitate reaction between a relatively finely divided solid and a gas.

The principal object of the invention is to provide a nozzle or injector device for introducing a dispersion of finely divided material into a reaction chamber. The invention aims to provide a feed nozzle of this character, simply constructed and designed to distribute a dispersion of material over any desirable area.

One operation in which the nozzle of the invention may be used to particular advantage is in the roasting of sulfide ore fines in gaseous suspension to produce sulfur dioxide gas. In processes of this nature, it will be understood the finely divided ore is injected into the roasting or combustion chamber, and air is supplied to furnish oxygen for roasting the ore. To illustrate, ore may be fed into the upper part of a reaction chamber and the air employed for roasting introduced into either the top or bottom of the combustion chamber as desired. The finely divided ore may be introduced into the reaction chamber by a mechanical feeder, or may be injected by means of a jet of inert gas such as steam, or by a stream of air, in which latter case the relatively small amount of air employed is utilized in the roasting operation. In roasting operations of this kind, it is highly desirable to bring about satisfactory distribution of ore particles in the reaction chamber so as to provide adequate dispersion of ore in the oxidizing gas, and thus promote efficient roasting of the ore.

For convenience, a nozzle constituting one embodiment of the invention is described for illustrative purposes in connection with the roasting of finely divided sulfide ores, although it is to be understood the principles of the invention may be employed in formation of dispersions of solid or liquid materials for any purpose.

The invention comprises the features of construction, combinations of elements, and arrangement of parts exemplified in the construction herein described. The objects and advantages of the invention will appear from the following description taken in connection with the accompanying drawings, in which

Fig. 1 is a longitudinal, vertical section show-

ing a feed nozzle of the invention associated with a sulfide ore fines burner;

Fig. 2 is an elevation taken approximately on the line 2—2 of Fig. 1;

Fig. 3 is a horizontal section taken approximately on the line 3—3 of Fig. 1;

Fig. 4 is a longitudinal, vertical section taken approximately on the lines 4—4 of Figs. 3 and 5, showing in detail the construction of the feed nozzle;

Fig. 5 is a horizontal section taken approximately on the line 5—5 of Fig. 4, and

Fig. 6 is a plan view of a shim, the purpose of which will hereinafter appear.

Fig. 1 shows a portion of a fines ore burner 15 wall comprising a lining 10 of refractory material and an exterior steel shell 11. As shown in elevation in Fig. 2, the burner wall is provided with a rectangular opening 12 to accommodate the feed nozzle, indicated generally by 14, and associated parts thereof. As indicated at 15 and 16, Figs. 1 and 3, the edges of lining 10 adjacent opening 12 are bevelled off to permit admission of a diverging sheet-like stream of ore and air into the combustion chamber of the burner. 25

Projecting outwardly from shell 11 is a rectangular collar 17 welded on one edge as at 18 to the burner shell, and formed at the opposite edge with a flange 20 to which is detachably connected by rivets or bolts 21, a plate 22 supporting the feed nozzle 14 and associated parts. Attached by bolts 25 to plate 22 near the lower edge is an angle iron 26 shown in section in Figs. 1 and 4, in elevation in Fig. 2, and in plan in Fig. 5. The horizontal flange 27 of angle iron 26 supports nozzle 14 and holds the same in proper position in the burner wall port 12. It will be understood plate 22 is provided with a suitably shaped opening 30 (Fig. 3) to permit insertion of feed nozzle 14 to rest in the position shown in Fig. 1. 35

Details of construction of nozzle 14 may be understood from consideration of Figs. 4 and 5. Referring particularly to Fig. 4, the nozzle includes a vertically positioned cylindrical casing 31 grooved at either end as at 32 and 33 to receive discs 35 and 36. The lower part of cylinder 31 is bored out to provide a shoulder 38 against which the circular edge of a plug 40 is seated. Plug 40 comprises a cone-shaped surface 41 and a short cylindrical section 42, the circular lower edge of cone-shaped surface 41 intersecting the vertical inner wall of casing 31. When assembling the nozzle, the plug 40 is inserted against shoulder 38 and welded to cylindrical casing 31 as in- 55

dicated at 44. Plates 35 and 36 are then tightly wedged in place, thereby providing above cone-shaped plug 40 an upper material feeding chamber 46, and a lower gas compartment 48.

5 As shown in Fig. 4, the lower end of cylinder 31 is seated in a depression 52 in a circular plate 53. By means of rivets 54, plate 53 is rigidly connected to horizontal flange 27 of angle iron 26. As casing 31 is wedged tightly in depression 10 52, it will be seen the nozzle is thus held by plate 53 in the position shown in Figs. 1 and 2.

15 The wall of cylinder 31 remote from the interior of the burner is tapped at 56 to receive the end of a pipe 57, having a control valve 58, through which gas may be introduced into lower compartment 48.

20 Adjacent the intersection of the lower circular edge of the cone-shaped surface 41 and the inside wall of the upper compartment 46 is an arcuate slot 60 to permit discharge of material from feeding chamber 46. Slot 60 extends horizontally through an angle A, as indicated in Fig. 5. The vertical dimension and the length of slot 60 may be proportioned to permit feeding into 25 the roasting chamber of any desired quantities of material, the length of the slot being selected to provide the desired lateral or sidewise dispersion of the material fed into the chamber. A curved member 62, triangular in cross-section, 30 may be placed on the lower horizontal edge of slot 60 to continue surface 41 to the outside of casing 31. At the front of lower compartment 48 and just below slot 60 is a second slot 61 through which gas is discharged from compartment 35 48 into the stream of material flowing through slot 60. As seen in Fig. 5, slot 61 subtends an angle B which is preferably appreciably greater than angle A. The purpose of this construction will presently appear.

40 Reference numeral 63, Fig. 4, indicates a circular dispersion plate, encircling cylinder 31, and having at the rear side a cut-out section 64 to accommodate air feed pipe 57. Plate 63 loosely contacts the outer surface of cylinder 31, and 45 may be vertically adjusted without disassembling the unit by inserting or withdrawing one or more semi-circular shims 67 shown in section in Fig. 4 and in plan in Fig. 6.

50 The upper cover plate 35 of the nozzle is centrally tapped to receive the lower end of a conduit 70 through which ore is fed into compartment 46 from a hopper 71. Rate of flow of ore into compartment 46 may be controlled by valve 72.

55 Danger of overheating the nozzle and the ore feed pipe 70 and plate 22 is largely avoided by a metal shield 75 and firebrick block 76. Shield 75 may comprise a vertically positioned half-round section of steel 77 fitting at the lower end 60 78 over the inner upper vertical surface of casing 31, and having in the upper end a semi-circular disc 79 welded thereto. As shown at 80 in Fig. 3, and at 81 in Fig. 1, the edges of the shield are welded to the inner side of supporting plate 65 22. Firebrick block 76 may be generally rectangular in shape as indicated in Figs. 2 and 3, and is provided on the rear face with a cutout portion to receive shield 75. Block 76 is held in place 70 against plate 22 by bolts 85.

75 The feed nozzle illustrated may be used in practice substantially as follows: In the roasting of sulfide ores in gaseous suspension, one of the important problems involved is the formation of a satisfactory dispersion of the finely divided ore 75 in the roasting atmosphere in the combustion

chamber. When employing a nozzle of the present invention, for example in roasting sulfide ores, it will be understood the nozzle may be placed in a vertical side wall of the furnace near the top of the roasting chamber.

5 Ore is fed from hopper 71 into upper chamber 46 of nozzle 14 at any desired rate determined by adjustment of valve 72. Air for injecting the ore into the roasting chamber is introduced into lower compartment 48 of the nozzle through pipe 10 57, and the air pressure in chamber 48 is controlled by adjustment of valve 58. In the present example, it will be understood the air in chamber 15 48 is employed primarily for injecting the ore into the furnace and dispersing the ore in the 20 roasting atmosphere, but not for supplying the bulk of the air needed to support oxidation of the ore, such air being introduced into the combustion chamber through separate ports or inlets not shown. Accordingly, it is evident gases other 25 than air, steam for example, may be introduced into compartment 48.

At the beginning of operations, the rear part 30 of material feed chamber 46 fills up with ore as indicated at 86. Thereafter all of the ore fed into chamber 46 flows downwardly over the forward face of conical surface 41, and passes through arcuate slot or orifice 60. As will be understood from Figs. 3 and 5, the length of slot 60 (angle A) is chosen, according to the size of the particular combustion chamber, so as to provide for any desired lateral spread of the ore, (i. e. lateral spread in a horizontal plane and in directions indicated by the arrows 88, Fig. 3). It will be seen the ore is thus continuously discharged 35 through slot 60 in the form of a thin, even, downwardly directed, arcuate sheet. Issuing from slot 61 is a horizontal, arcuate or fan-shaped sheet of air or other gas, the air stream intersecting the underside or concave surface of the ore sheet approximately in the horizontal plane of slot 61. The particles of ore are swept up by the air stream, and there is thus formed a relatively 40 horizontally disposed, substantially fan-shaped dispersion of ore which is charged into the combustion chamber in a diverging stream. As previously noted, the gas slot 61 is longer than ore slot 60, the purpose of this being to control side-wide throw of the material being fed, by providing bordering margins of air along the diverging 45 edges of the ore stream thus preventing ore particles falling off the outer edges of the air sheet introduced through slot 61, and dropping more or less directly into the roasting chamber along the furnace wall adjacent the feed 50 nozzle. In practice, the slot 61 may be for example 20° longer than slot 60.

The longitudinal travel or horizontal distance of projection of the ore particles from the nozzle may be controlled by adjustment of the rate of 55 feed of ore through slot 60, and of the gas pressure in chamber 48, and of the vertical position of the upper surface of deflecting plate 63. It is generally desirable to place plate 63, which may be made of any kind of abrasion resistant material, so that at least some of the ore particles impinge on the plate, and are shot off the face of the plate in a substantially horizontal direction. By vertically adjusting the surface of plate 63, the extent of the longitudinal horizontal projection of the ore particles may be readily controlled. When plate 63 is in a lower position, longitudinal horizontal throw of ore particles is lessened, and when the plate 63 is in a higher position, longitudinal horizontal projection of ore particles is 70 75 80 85 90 95 100

increased. To provide for particular operating conditions involved, such as the size of the combustion chamber, the plate 63 may be vertically adjusted without dismounting the nozzle and without interfering with the ore feeding operation by inserting or withdrawing one or more semi-circular shims 61 between plate 63 and plate 53. In this way, plate 63 may be vertically adjusted, and the desired longitudinal, horizontal throw of the ore particles obtained.

The nozzles of the invention are simple in design, and easily manufactured and assembled. According to the size or shape of the reaction chamber in connection with which the nozzles may be employed, the lengths of the ore and gas discharge slots and the adjustment of the deflecting plate may be chosen to meet any operating requirements. Parts of the nozzle, except the deflecting plate, are not subjected to the abrasive action of the material being distributed. The deflecting plate may be readily replaced if necessary. The nozzles of the invention may also be employed to advantage in forming dispersions of any liquid or solid materials.

We claim:

1. Apparatus for distributing materials comprising a unitary casing, a chamber in the casing, a slot in the side of the casing, a surface in the chamber for feeding material through said slot, a second chamber in said casing adapted to contain fluid and a second slot longer than the first in the casing communicating with said second chamber, said slots being positioned so that fluid discharged through the second slot is introduced into material discharged through the first slot.

2. Apparatus for distributing materials comprising a cylindrical casing, a chamber in the casing, a slot in the side of the casing lying in a plane disposed at a right angle to the axis of the casing, a cone-shaped surface in the chamber for feeding material through said slot, a second chamber in said casing adapted to contain fluid and a second slot in the casing communicating with said second chamber and lying in a plane disposed at a right angle to the axis of the casing, said slots being positioned so that fluid discharged through the second slot is introduced into material discharged through the first slot, said second slot being sufficiently larger than the first to maintain marginal streams of fluid along the edges of the stream of material discharged through the first slot, and a plate for deflecting material positioned so that at least some of the discharged material impinges thereon.

3. In combination with a reaction chamber having an opening in the wall thereof, a nozzle in the opening for introducing material into the chamber, said nozzle comprising a vertically disposed cylindrical casing, a material chamber in the upper part of the casing, a horizontal arcuate slot in the casing wall opening toward said reaction chamber, a cone-shaped surface in the material chamber for feeding material through said slot, a second chamber in the casing adapted to contain fluid and a second horizontal arcuate slot in the casing wall opening toward said reaction chamber and communicating with the fluid chamber, said second slot being disposed beneath the first slot and being sufficiently longer than the first slot to maintain marginal streams of fluid along the edges of the stream of material discharged through the first slot, a deflecting plate beneath the second slot, said slots and deflecting plate being arranged so that fluid discharged through the second slot is introduced into mate-

rial discharged through the first slot to charge into the reaction chamber a fan-like dispersion of material.

4. Apparatus for distributing materials comprising an opening shaped to form a curved sheet of material, means for feeding material through said opening, a deflecting surface adjacent the opening, a second opening between the deflecting surface and the first-mentioned opening for introducing a stream of fluid into the concave surface of the material, and means for altering the position of said deflecting surface with respect to said opening.

5. Apparatus for distributing materials comprising a relatively cone-shaped downwardly sloping surface having a curved lower edge, means for supplying material to an upper part of the surface to cause material to flow downwardly over said surface and form adjacent the lower edge thereof a curved sheet of material, means for injecting into the concave surface of the material at an angle to said surface a stream of fluid to form a diverging dispersion of material, a surface for deflecting the material positioned so that at least some of the material impinges thereon, and means for maintaining a marginal stream of fluid along the edges of the dispersion.

6. Apparatus for distributing materials comprising an opening shaped to form a curved sheet of material, means for feeding material through said opening, a deflecting surface adjacent the opening, a second opening between the deflecting surface and the first-mentioned opening for introducing a stream of fluid into the concave surface of the material, means for altering the position of said deflecting surface with respect to said second opening, and means for maintaining a marginal stream of fluid along the edges of the material.

7. Apparatus for distributing materials comprising means for forming a curved sheet of material, means for introducing into the concave surface of said sheet at an angle thereto a stream of fluid to form a diverging fan-like dispersion of material, and means for maintaining marginal streams of fluid along the diverging edges of the dispersion.

8. Apparatus for distributing materials comprising an elongated opening shaped to form a curved sheet of material, means for feeding material through said opening, a deflecting surface adjacent the opening, and a second elongated opening longer than the first-mentioned opening between the deflecting surface and the first-mentioned opening for introducing a stream of fluid into the concave surface of the material.

9. Apparatus for distributing materials comprising a unitary casing, a chamber in the casing, a slot in the side of the casing, a surface in the chamber for feeding material through said slot, a second chamber in said casing adapted to contain fluid and a second slot in the casing communicating with said second chamber, said slots being positioned so that fluid discharged through the second slot is introduced into material discharged through the first slot.

10. Apparatus for distributing materials comprising a cylindrical casing, a chamber in the casing, a slot in the side of the casing lying in a plane disposed at a right angle to the axis of the casing, a cone-shaped surface in the chamber for feeding material through said slot, a second chamber in said casing adapted to contain fluid and a second slot in the casing communicating with said second chamber and lying in a plane

disposed at a right angle to the axis of the casing, said slots being positioned so that fluid discharged through the second slot is introduced into material discharged through the first slot, and a plate 5 for deflecting material positioned so that at least some of the discharged material impinges thereon.

11. In combination with a reaction chamber having an opening in the wall thereof, a nozzle 10 in the opening for introducing material into the chamber, said nozzle comprising a vertically disposed cylindrical casing, a material chamber in the upper part of the casing, a horizontal arcuate slot in the casing wall opening toward said re- 15 action chamber, a cone-shaped surface in the

material chamber for feeding material through said slot, a second chamber in the casing adapted to contain fluid, a second horizontal arcuate slot in the casing wall opening toward said reaction chamber and communicating with the fluid chamber, said second slot being longer than and disposed beneath the first slot, a deflecting plate 5 beneath the second slot, said slots and deflecting plate being arranged so that fluid discharged through the second slot is introduced into material discharged through the first slot to introduce into the reaction chamber a fan-like dispersion of material.
